Primary Examiner—Martie K. Holtje
Attorney, Agent, or Firm—Fish & Richardson P.C.**[57] CLAIM**

The ornamental design for a tip for correction fluid applicator, as shown and described.

DESCRIPTION

FIG. 1 is a perspective view of a tip for a correction fluid applicator showing my new design;

FIG. 2 is a front plan view of the tip of FIG. 1;

FIG. 3 is a rear plan view of the tip of FIG. 1;

FIG. 4 is a first side plan view of the tip of FIG. 1;

FIG. 5 is an opposite side plan view of the tip of FIG. 4; and, FIG. 6 is a bottom plan view of the tip of FIG. 1.

The broken lines showing of the stem and cap of an applicator for a correction fluid are for illustrative purposes and form no part of the claimed design.
